DESIGN.

D. COLESTOCK.
RADIATOR.

No. 20,444.

Patented Jan. 6, 1891.

20,444.—RADIATOR.—*Daniel Colestock, Titusville, Pa.* Application filed November 21, 1890. Serial No. 372,259. Term of patent 7 years.

UNITED STATES PATENT OFFICE.

DANIEL COLESTOCK, OF TITUSVILLE, PENNSYLVANIA.

DESIGN FOR A RADIATOR.

SPECIFICATION forming part of Design No. 20,444, dated January 6, 1891.

Application filed November 21, 1890. Serial No. 372,259. Term of patent 7 years.

To all whom it may concern:

Be it known that I, DANIEL COLESTOCK, a citizen of the United States, residing at Titusville, in the county of Crawford and State of Pennsylvania, have invented and produced a new and original Design for Radiators, of which the following is a specification, reference being had to the accompanying photograph, forming part thereof.

5 My design relates to sectional radiators, where the end of the radiator or outer side of the end section presents a plane or paneled surface the entire width of the radiator, my invention consisting in ornamenting the end

with embossed or depressed figures or scroll-work, thereby presenting a pleasing effect to the eye.

15 The accompanying photograph is a perspective view of my radiator ornamented as herein described.

I claim as my invention—

20 The design for the ornamentation of a radiator, as herein shown and described.

DANIEL COLESTOCK.
